RADIO RECEIVER

Alfred Leonard Green, Ashfield, Sydney, New South Wales, Australia, assignor to Amalgamated Wireless (Australasia) Limited, Sydney, New South Wales, Australia, a company of New South Wales, Australia

Application July 8, 1941, Serial No. 401,406
In Australia July 26, 1940

5 Claims. (Cl. 250—20)

This invention relates to radio receivers and more particularly to radio receivers of the type adapted to receive signals over a plurality of wavelength ranges or bands.

In receivers of this type, where for economical or other reasons only a limited number of valves are to be employed, the problem arises of providing adequate amplification for the weak signals which are customarily obtained on the higher frequency or so-called short-wave ranges.

This problem is accentuated by the fact that the sensitivity of receivers of this type varies from band to band, the gain being lower on the higher frequency bands than on the lower or medium frequency broadcast bands.

In order to obtain comparable performance on all bands the sensitivity of the receiver must be made higher on the high frequency bands than on the lower. This requirement limits the minimum number of valves which may be employed in any receiver of the type referred to, to that number which will provide the desired sensitivity on the short wave bands.

This is not a very satisfactory arrangement because to obtain sufficient receiver gain in the short wave band, the amplifying means must be such as to provide much more gain at the lower frequencies than is required and further difficulties are introduced in controlling this surplus gain.

One suggestion for overcoming the difficulty of providing sufficient gain on the high frequency bands, without affecting the normal design of the receiver on the broadcast band, has been to combine with the wave selector switch, means for switching into operation an additional amplifying stage only when the wave selector switch is adjusted to provide reception on the H. F. bands. This arrangement is quite effective in achieving its purpose but is uneconomical inasmuch as it necessitates the introduction of an additional valve and associated circuit equipment over that normally required to provide satisfactory reception on the medium wave broadcast band.

It has also been suggested to increase the sensitivity in a receiver employing a limited number of valves by the use of a circuit arrangement in which the signal is amplified both before and after detection in the same amplifier valve or valves. This is the well-known reflex circuit and whilst it provides a means of economically realising the added sensitivity required on the short wave bands, it also increases the sensitivity on the medium wave band and as a result introduces undesirable defects into the receiver output on that band. The most noticeable defect is the in-

ability to control the output volume to zero and the marked increase in distortion as the receiver output volume is reduced.

These defects are introduced by reason of the fact that in practice it is not usually possible to secure a valve for use in the reflex circuit, which has linear amplifying characteristics over a wide range of input potentials. Consequently an undesirable rectification takes place within this valve when the stronger input potentials, customarily received on the medium wave band, are subjected to the increased amplification brought about by the reflex circuit arrangement.

These defects are not particularly evident on the short wave band because the input potentials on this band are usually of much smaller amplitude and the sum of the R. F. and A. F. potentials applied to the input of the reflex valve is within the linear operating characteristics of the valve.

It is an object of this invention to provide an improved receiver of the type referred to in which satisfactory performance characteristics may be economically obtained on all bands when using only the minimum number of valves required to provide satisfactory reception on the medium wave broadcast band.

A further object of the invention is to provide an improved circuit arrangement for a receiver of the type referred to in which the sensitivity of the receiver when operated on the short wave bands is greater than that employed for the reception of signals on the medium wave broadcast band.

A still further object of the invention is to provide means whereby the essential circuit components employed for increasing the sensitivity of the receiver on the short wave band may be utilized to increase the selectivity on the broadcast band.

The above objects are achieved, in accordance with this invention, by an improved circuit arrangement, for a receiver of the type referred to, and comprising means whereby a valve, employed to amplify only L. F. energy on the broadcast band, is utilized to amplify both high and L. F. energy on the short wave band.

In carrying out the invention, the audio frequency amplifying valve, which amplifies the demodulation output of the carrier frequency rectifier on the broadcast band, is employed in a reflex circuit for amplifying both high and L. F. energy on the short wave band, the arrangement being such that an additional radio frequency transformer, necessitated by the reflex connection on the short wave band, forms part of a band

pass filter network for increasing the selectivity of the receiver on the broadcast band.

For a more complete understanding of the invention and the manner in which it is to be carried out, reference will now be made to the following description in conjunction with the accompanying drawings.

In order to simplify the description, only that portion of the circuit of a multi-wave superheterodyne receiver, which is essential to convey an understanding of the invention, is shown in the said drawings in which Figures 1 and 2 are circuit diagrams illustrating by way of example two embodiments of the invention.

Referring now to Figure 1 of the said drawings, modulated intermediate frequency energy is fed to the terminals 2-4 from the preceding stages 5 of the receiver.

The detail circuit arrangement of the tuning, amplifying and detecting portions of the preceding stages 5 are so well known that further description is considered unnecessary. It is sufficient for the purpose of this invention to indicate that wave selector means 6 are provided in the preceding stage 5 to cover a plurality of wave bands.

The switching devices 8, 9, 10, which are provided for the purpose of effecting the required circuit alterations in accordance with this invention, are preferably ganged with the wave selector means 6 for simultaneous rotation therewith as indicated by the link 7. Whilst this is the preferred arrangement it is to be clearly understood that if desired, the switching devices 8, 9, 10 only may be ganged together for operation independently of the wave selector switch 6.

When the wave selector switch 6 is adjusted for reception of signals in the broadcast band, the switching devices 8, 9, 10 are adjusted to the position MW shown in the drawing. In this position the intermediate frequency energy applied to the terminals 2, 4 is passed to the carrier frequency rectifier 21 through a filter network comprising the transformers 11, 12.

The primary windings 13, 15 and secondary windings 14, 16 respectively of the transformers 11, 12 are tuned to resonate at the desired intermediate frequency by means of the condensers 28, 31 and 29, 30 respectively.

The output secondary winding 14 of the transformer 11 is coupled to the input primary winding 15 of the transformer 12 across the coupling condensers 32, 33, the switch section 9 and the lead 34. By the use of this filter network the receiver selectivity is considerably increased. The value chosen for condensers 32 and 33 determines the degree of coupling between the two transformers 11, 12. Increasing the value of 32 and 33 decreases the coupling whereby the selectivity is increased and the sensitivity reduced. The amount of sensitivity required therefore usually determines the final value of 32 and 33.

Intermediate frequency signals in the secondary circuit 16, 39 of the transformer 12 are supplied to the demodulating rectifier 60. The latter is of the diode rectifier type comprising an anode electrode 21 and a cathode 19. The diode rectifier 60 is provided with an output resistor 36 included in series between the low potential terminal 40 of the secondary circuit 16, 39 and a lead 18 is connected with the cathode 19. The output resistor 36 is provided with a suitable intermediate frequency by-pass capacitor 37 and an intermediate frequency filter comprising a series

filter resistor 38 and a second by-pass capacitor 39 to the lead 18 from the terminal 40.

The circuit for the demodulator may be traced from the anode 21, which is connected with the high potential terminal 41 of the secondary circuit 16, 39, through the secondary circuit to the terminal 40, thence through the filter resistor 38 and the output resistor 36 to the cathode lead 18 and the cathode 19.

In the present example the diode rectifier 60 is shown as one of a pair of independent diode anodes 20-21 which are included in the envelope 27, common also to an amplifying valve having a cathode 19 in common with the diodes 20, 21 and having a control grid 22, a screen grid 23, a suppressor grid 25 and an output anode 26. The diode anodes 20, 21 are disposed adjacent a portion of the cathode 19 which only provides an electron stream to said anodes 20, 21. The multiple valve described is the well known double diode pentode.

Although the amplifier and rectifiers housed within the single envelope 27 are shown as a pentode and diodes respectively, it is to be understood that any suitable form of amplifier or rectifier other than a pentode or diode may be utilised to constitute the multiple assembly. Furthermore, separate valves may be employed if desired without affecting the scope of this invention.

As is well understood, modulated intermediate frequency signals received through the filter network 11, 12 are applied to the diode rectifier 60 through the input circuit 16, 39 and the audio frequency components thereof appear across the output resistor 36. The output resistor 36 is arranged as a volume control potentiometer having a variable contact 42. Audio frequency signals from the volume control contact 42 are applied to the grid 22 through a coupling capacitor 43, which is connected to the junction point 44 of the input coupling resistors 46, 45 whose other ends are connected to grid 22 and ground 48 respectively.

Biassing potentials are applied to the grid 22 through the resistors 45, 46 from any suitable source, such as the self-bias resistor 49, in the cathode return lead 18. The self-biassing resistor 49 is shunted by a suitable radio frequency and audio frequency by-pass condenser 50.

The suppressor grid 25 is joined to the cathode 19 through the lead 51 while the screen grid 23 is connected at 57 to a suitable positive potential supply source (not shown) in known manner.

The anode 26 is connected through the anode load resistor 52 to the moving arm of the switch 10. With the switch 10 in the position MW shown in the drawings, i. e. for reception on the broadcast band, operating potentials are applied to the anode 26 through the switch 10 and the load resistor 52 from the positive terminal 54 of a potential supply source (not shown).

Amplified audio frequency potentials appearing across the anode load resistor 52 may be applied through the R. F. choke 61 and the lead 55 either directly or after still further amplification to the utilisation means (not shown).

From the foregoing description it will be seen that when the wave selector switch is adjusted for the reception of signals in the medium wave broadcast band the amplifier section of the valve 27 functions solely to amplify the audio frequency potentials applied to its input from the output circuit of the demodulating rectifier 60, the modulated I. F. being applied to said rectifier, through

a filter network, whereby the selectivity of the receiver is considerably increased.

When the wave selector switch 6 is adjusted for reception on the shortwave band, the switches 8, 9, 10 are adjusted to the alternative positions SW shown in the drawing. With the switches in this position the circuit arrangement of the portion of the receiver indicated in the drawing is altered so as to cause the amplifying section of the valve 27 to amplify the signals both before and after rectification. Thus the sensitivity of the receiver on the short-wave bands is considerably greater than the sensitivity it would be possible to obtain if the circuit arrangement for these bands was maintained the same as that employed for reception on the medium wave broadcast band.

More specifically when the wave selector switch 6 is adjusted for reception on the short wave band the switches 8, 9, 10 are also adjusted to the alternative positions SW. Modulated I. F. energy applied to the terminals 2, 4 is passed through the transformer 11 across the switch 8 and the blocking condenser 47 to the grid 22. The amplified energy appearing in the output circuit 24 is applied through the R. F. by-pass condenser 53, the switch section 10 and the coupling transformer 12, to the demodulating rectifier 60. The A. F. signal potentials across the output load resistor 36 are applied to the grid 22 from the variable contact 42 through the coupling condenser 43 and the grid coupling resistors 45, 46 via junction point 44.

The A. F. potentials applied to the grid 22 are simultaneously amplified with the high frequency potentials in the amplifier and appear in amplified form across the anode load resistor 52 and are passed to the utilization means (not shown) through the R. F. choke 61 and the lead 55 in the same manner as that employed on the medium wave broadcast band.

Operating potentials are applied to the anode 26 in this arrangement of the circuit from the positive terminal 56 of a suitable potential supply source (not shown), through the primary winding 15 of the coupling transformer 12, the switch section 10, the load resistor 52 and the lead 24. The condenser 53, which is connected between the low potential end of the primary 15 and ground 48, provides an effective by-pass for I. F. energy at that point.

From the foregoing description of the circuit alterations effected by operation of the switches to the SW positions, it will be seen that the coupling transformers 11, 12, instead of forming a single highly selective filter network as on the medium wave broadcast band with said switches set at the MW positions are now employed as individual interstage coupling transformers in a well-known reflex circuit. The coupling condensers 32, 33, in the altered (SW) circuit arrangement, function as blocking condensers to prevent short circuiting of the high voltage potentials supplied to the anode 26 from the terminal 56.

From the foregoing description it will be seen that in the SW position of the switches 8, 9, 10, increased sensitivity is obtained with a limited number of valves by the use of a reflex circuit in which the amplifier valve 27 is caused to function as an amplifier of the signal energy both before and after rectification.

In the MW position of the switches, the reflexing function is removed, thus eliminating a stage of I. F. amplification and causing the valve 27 to function as an A. F. amplifier only. In order to compensate for the loss in selectivity occasioned

by the elimination of the stage of I. F. amplification, the I. F. coupling transformer 12, which was employed in the reflex circuit, is utilised in this position of the switches to form part of a selective filter network.

As only one diode 21 is required for detection, the second diode (20) may be fed with H. F. potentials from a suitable point in the H. F. amplifier circuit and used to provide A. V. C. bias for preceding carrier frequency stages. On the other hand, the two diode anodes 20, 21 may be conductively coupled together and the desired A. V. C. potentials obtained from a suitable point in the diode load circuit in known manner.

Furthermore, it will be appreciated that the scope of the invention is not limited to the arrangement described. For example, if the switches 8, 9, 10 are ganged together for operation independently of the wave selector switch 6, it is possible to utilize the added sensitivity which is obtainable in the SW position to receive weak medium wave broadcast signals. Also, if with said switches 8, 9, 10 in the SW position, strong signals are received which produce distortion due to the reflex connection, said distortion may be avoided by moving said switches to the MW position thereby removing the reflexed connections.

The circuit arrangement shown in Figure 1 has the disadvantage that the I. F. potential difference across the primary winding 15 of the transformer 12 is applied across the input circuit of the output valve (not shown) and necessitates the use of the radio frequency choke 61.

The arrangement illustrated in Figure 2 however removes this disadvantage by providing the switch 10 with an additional section 10a and arranging the circuit connections to the individual sections 10 and 10a so that, in the SW position of the switch, the relative positions of the winding 15 and the anode resistor 52 in the output circuit of the valve 27 are reversed to those shown for the corresponding position of the switch 10 in Figure 1.

In Figure 2 the R. F. bypass condenser 53 is removed from the simple shunt connection across the anode resistor 52, (as shown in Figure 1) and is now connected between the primary coil 15 and earth 48, thus improving the fidelity of the receiver when the respective switches are in the MW position.

On account of the new connection of the anode resistor 52 in Figure 2, the desired coupling between the coils 14 and 15, when the switches are in the MW position is effected by means of the coupling coils 32a, 33a and the double link connecting leads 34, 34a. This necessitates the use of an additional section 9a in the switch 9 so that both leads 34, 34a may be broken in the SW position of the switches. The coupling coils 32a and 33a may consist of a few turns of wire magnetically coupled to the tuned coils 14, 15 respectively.

With the exception of the differences outlined above, the arrangement of the circuit of Figure 2 and the method of operation agrees with that already described in connection with Figure 1.

What I claim is:

1. A radio receiver comprising in combination, a source of modulated carrier frequency energy, a demodulating detector having an input and an output circuit, an amplifying valve having an input and an output circuit, means for coupling the input of the said amplifying valve to the output of said demodulating detector to receive

audio frequency energy therefrom, a first radio frequency coupling transformer having a primary and a secondary winding, the primary winding being connected to receive energising potentials from said source of modulated carrier frequency, a second radio frequency coupling transformer having a primary and a secondary winding, the latter secondary winding being coupled to the input of the said demodulating detector, and a plurality of switching devices, mechanically linked together for simultaneous operation, constructed and arranged, in one operating position, to connect the secondary of said first radio frequency transformer to the primary of said second radio frequency transformer through a common coupling impedance, and in a second operating position, to connect the secondary winding of said first mentioned transformer to the input of said amplifying valve and to connect the primary winding of said second radio frequency transformer in series with the output circuit of said amplifying valve.

2. A radio receiver as claimed in claim 1, adapted for operation in a plurality of bands, characterised in that the said switching devices are mechanically linked with a wave range selector switch for simultaneous operation therewith, the arrangement being such that the said second operating position of said switching devices coincides with the selection of the short wave range by said wave range selector switch.

3. A multi-band modulated-carrier signal receiver tunable over a high-frequency band and one or more low-frequency bands comprising, a multi-band carrier-frequency selector system, an amplifier, a signal-translating stage, first and second transformers, a link circuit coupling said transformers and means for selectively coupling the output of said selector system to said translating stage, in the order named either through said first transformer, said link circuit, said second transformer and said amplifier and for simultaneously conditioning said selector system

for operation in said low-frequency band or bands, or through said first transformer, said amplifier, said second transformer and said amplifier and for simultaneously conditioning said selector system for operation in said high-frequency band.

4. A multi-band modulated-carrier signal receiver tunable over a high-frequency band and one or more low-frequency bands comprising, a multi-band carrier-frequency selector system, an amplifier, a demodulator, a signal-translating stage, first and second transformers, a link circuit coupling said transformers, and means for selectively coupling the output of said selector system to said translating stage, either through said first transformer, said link circuit, said second transformer, said demodulator and said amplifier and for simultaneously conditioning said selector system for operation in said low-frequency band or bands, or through said first transformer, said amplifier, said second transformer, said demodulator and said amplifier and for simultaneously conditioning said selector system for operation in said high-frequency band.

5. A multi-band superheterodyne signal receiver tunable over a high-frequency band and one or more low-frequency bands comprising, a multi-band carrier-frequency selector system, an amplifier, a demodulator, a signal-translating stage, first and second coupling means, switch means for selectively conditioning said receiver for operation in any of said bands, switch means for selectively coupling the output of said selector system to said translating stage, in the order named either through said first coupling means, said second coupling means, demodulator and amplifier for operation in said low-frequency band or bands, or through said first coupling means, said amplifier, said second coupling means, demodulator and amplifier for operation in said high-frequency band, and unicontrol means for operating said switch means.

ALFRED LEONARD GREEN.
